MAGNETIC SOUND TRANSLATING SYSTEM

William P. Lear, North Hollywood, Calif., assignor,
by mesne assignments, to Lear, Incorporated,
Grand Rapids, Mich., a corporation of Illinois

Application May 22, 1945, Serial No. 595,240

20 Claims. (Cl. 179—100.2)

1

This invention relates to magnetic recording systems and more particularly to a magnetic sound translating unit for use in a magazine type recording system.

The present sound translating unit is particularly adaptable for use with the magazine described and claimed in my copending application Serial No. 593,378 filed May 12, 1945, now Patent No. 2,424,697, issued July 29, 1947, for "Magnetic recorder," and assigned to the same assignee as is this case. As described in said copending application, the magazine contains a pair of spaced reels for traversing a linear magnetic recording medium, such as a magnetic wire, with respect to a magnetic translating head, and also contains spooling mechanism for winding the wire in layers onto and off the reels.

The unit of the present invention comprises driving mechanism and electronic sound translating components cooperable respectively with the driving and spooling mechanism of such magazine and with the magnetic translating head thereof. The unit of the present invention may be used for either recording or reproducing sound, and includes novel combined electrical and mechanical controls for selectively conditioning the recording system for rewinding, sound recording, or sound reproducing.

It is among the objects of this invention to provide a sound translating unit for use with a magazine type magnetic recording system; to provide such a sound translating unit interchangeable with any one of a plurality of magazines containing a magnetic recording medium and reels for traversing the same with respect to a magnetic recording head; to provide such a unit including means for automatically stopping the reel driving mechanism when the wire in the magazine has been completely rewound from one reel onto the other reel; to provide such a sound translating unit including a novel control unit for electrically and mechanically conditioning the translating unit for either recording or reproducing sound or for rewinding the recording medium onto a rewind reel in the magazine; to provide such a translating unit including gear reduction means associated with the reel driving mechanism for operating spooling mechanism in the magazine at a reduced rate of speed with respect to the reel driving means; to provide such a unit including latching means automatically engageable with a magazine when the latter is placed in cooperative relation with the translating unit; and to provide a simple, easily serviced, light

weight sound translating unit for use with a magazine type recording system.

These and other objects, advantages and novel features of the invention will be apparent from the following description and the accompanying drawings. In the drawings:

Fig. 1 is a perspective view illustrating the unit of the invention having a magazine engaged therewith.

Fig. 2 is a top plan view of a portion of the translating unit of the invention.

Fig. 3 is a vertical sectional view through the translating unit of the invention and a magazine associated therewith.

Fig. 4 is a bottom plan view of a driving mechanism forming part of the invention.

Fig. 5 is a transverse sectional view on the line 5—5 of Fig. 3.

Fig. 6 is a transverse sectional view on the line 6—6 of Fig. 3.

Fig. 7 is an elevational view, partly in section, on the line 7—7 of Fig. 6.

Fig. 8 is an elevational view, partly in section, on the line 8—8 of Fig. 6.

Fig. 9 is an elevational view, partly in section, on the line 9—9 of Fig. 5.

Fig. 10 is a schematic wiring diagram illustrating the motor control circuit of the unit.

Fig. 11 illustrates the indicating and switch operating mechanism.

Referring to the drawings, the sound translating unit 15 of the invention is shown in Fig. 1 as arranged with a magazine 20 in cooperative relation therewith. Unit 15 includes a base section 16, having a front panel 17, and a cover 18. Cover 18 is apertured as at 21 to expose a mounting plate 22 on which magazine 20 is placed.

Front panel 16 includes the controls for the unit such as a switch 23, a power connection 24, an indicating light 25, a jack 26 adapted to receive a plug connected to a microphone, an electro-mechanical control unit operating lever 27, and knobs 30, 31, 32 and 33 controlling operation of electrical and electronic components of the unit. A grill 34 conceals a loud speaker 39 incorporated in the unit.

As explained above, the unit of the present invention is particularly adapted to cooperate with a magazine 20 of the type described and claimed in my said copending application. Referring to Figs. 1 and 3, magazine 20 includes a base 35 having a cover 36 detachably secured thereto by screws 37, and provided with an aperture 38 containing a transparent window through which indicating mechanism registering the amount of

talking time available may be observed. Such indicating mechanism is described and claimed in my said copending application.

Magazine 20 contains a pair of reels 40 and 41 interchangeably receiving a magnetic recording wire 45 and secured to shafts 42 and 43 mounted on bearings in upstanding bosses 44 and 46 of base 35. On the lower end of each shaft 42, 43 is a coupling gear 47, 48, respectively detachably engageable with coupling gears 50 and 51 of unit 15. Coupling gears 47, 48, 50 and 51 are of the type described and claimed in my said copending application. Reels 40 and 41 are restrained against rotation, when magazine 20 is disengaged from unit 15, by bowed springs 52 and 53 secured to bosses 44 and 46. Normally, these springs engage the reels to hold the same stationary, and maintain wire 45 taut. When magazine 20 is engaged with unit 15, pins 54 and 55 on the unit enter apertures in the magazine to engage springs 52 and 53 respectively and compress the same out of engagement with the reels to provide for free rotation of the latter.

Reels 40 and 41 traverse wire 45 with respect to a magnetic translating head generally indicated at 60. Magazine 15 is further provided with transversally extending pins 56 at each corner thereof, which are engaged with pairs of latch bars 57, 58 in unit 15 to retain magazine 20 engaged with unit 15.

Referring to Figs. 2 and 3, a release bar 61 projects above the upper surface of cover 18 and is secured to a latch bar 58. Bars 57 and 58 are pivotally mounted at 62 and 63 respectively. A link 64 is pivotally interconnected to bar 51 above its pivot point and to bar 58 below its pivot point. Accordingly, when latch bar 61 is depressed, both bars 57 and 58 are moved inwardly to release pins 56 and permit magazine 20 to be disengaged from unit 15.

Unit 15 is more particularly shown in Figs. 2 through 9. Base portion 16 is provided with a central recess shown at 65 in Fig. 3 in which is secured a base plate 66, through coupling means indicated at 67. On either side of recess 65, electrical and electronic sound translating components may be mounted on base portion 16. A pair of pillars 68 and 70 interconnect base plate 66 to mounting plate 22. Base plate 66, as will be described more fully hereinafter, supports the driving mechanism for rotating coupling gears 50 and 51 and also for operating a spooling drive gear for the spooling mechanism in magazine 20.

Mounting plate 22, as previously explained, supports magazine 20. For this purpose, the mounting plate is formed with apertures 71 at each corner through which latching bars 51 and 58 project. These bars are interconnected in the same manner as described for the sound translating unit illustrated in my said copending application. Mounting plate 22 also is formed with apertures through which project coupling gears 50 and 51. These gears are provided with axially extending teeth having rounded outer edges for engagement with similarly formed coupling gears 47 and 48 of magazine 20. An electrical connection member such as a socket 72 is mounted on plate 22 for engagement with a suitable mating electrical connection member in magazine 20. Near its rearward edge, as viewed in Fig. 2, plate 22 is formed with an aperture 73 through which projects the operating arm 74 of a limit switch mechanism described more fully hereinafter. Immediately forward and to one side of aperture 73, an aperture 75 provides for projection of a

spooling mechanism drive gear 76 which cooperates with a similar gear in magazine 20 to operate spooling mechanism, elapsed time indicating mechanism and limit switch operating mechanism therein. The gear in magazine 20 drives a mechanism for level winding of the wire onto the respective spools depending upon whether the machine is recording and reproducing or rewinding. Such level layer winding means constitutes no part of the present disclosure and insofar as the instant case is concerned, such level winding means may take any of several forms known in the art and driven by gear 76. However, the gear 76 also drives the switching mechanism shown particularly in Figs. 10 and 11.

The driving mechanism in unit 15 for the reeling, spooling and indicating means of magazine 20 is shown more particularly in Figs. 3 through 6, and is motivated by a motor 80 which is mounted on a supporting plate 77 secured to base plate 66. The motor may be of the constant speed type customarily used for operating the turntables of electric phonographs and is provided with a friction driving roller 78 projecting beneath base 66. Roller 78 is selectively operable to drive either reel 40 or reel 41 through mechanism generally indicated at 85 (Fig. 4).

Pillar 68 is a hollow tubular member having upper and lower flanges 81 and 82 respectively secured to mounting plate 22 and base member 66, and contains bearings 83, 83 rotatably supporting a shaft 84 to which coupling gear 50 is secured for rotation. Gear 50 is movable axially of shaft 84 being normally urged outwardly by a spring 86. The gear may thus move inwardly when magazine 20 is engaged with unit 15, to provide intermeshing engagement with coupling gear 47 of the magazine in the event that there may be slight angular misalignment of the coupling gears. The rounded edges of the axially extending teeth of the gears facilitate this intermeshing engagement. Shaft 84 has a reduced portion 87 extending beneath base 66, and a hub member 88 is keyed to such reduced portion. A friction driving wheel 90 is mounted on hub 88 and a nut 91 secured to a threaded end 92 of shaft 84 maintains the hub and friction wheel assembled therewith.

Pillar 70 is likewise tubular and has a lower flange 93 secured to base 66 and an upper flange 94 secured to a gear housing 95. Bearings 96, 96 in pillar 70 rotatably support a shaft 97 having a reduced end 98 extending beneath base 66. A friction driving wheel 100, larger in diameter than driving wheel 90, is keyed to reduced portion 98 of shaft 97 and held thereon by a nut 101 threaded on the lower end 102 of shaft 97. Wheel 100 has a hub 103 to which is secured a friction collar 104 for a purpose to be described hereinafter.

The upper end of shaft 97 is reduced in diameter as indicated at 105 and coupling gear 51 is secured thereto for rotation with the shaft while being axially movable thereof. A spring 106 urges coupling gear 51 outwardly through an aperture in mounting plate 22.

Beneath gear 51, a spiral gear 107 is secured to shaft 97 and meshes with a spiral gear 108 on a shaft 110 extending at right angles to shaft 97. A worm 111 on shaft 110 engages a worm wheel 112 on a shaft 113 extending at right angles to shaft 110. Shaft 113 is suitably mounted in a bracket 114 forming part of gear housing 95. Spooling mechanism driving gear 76 is secured to the rearward end of shaft 113. Due to the speed

reduction afforded by gears 107, 108, worm 111 and worm wheel 112, gear 76 is rotated at a considerably reduced rate with respect to the rate of rotation of coupling gear 51. The spooling mechanism and associated elements in magazine 20 are thus operated at a reduced rate with respect to the rate of rotation of the reels in the magazine.

A bracket 115 is adjustably mounted on the lower side of base member 66. For this purpose, the bracket is provided with apertures 116 and 116 through which extend fastening members 117, 117 which are of less diameter than the lateral dimensions of apertures 116. Bracket 115 is therefore movable both laterally and longitudinally of base member 66.

Bracket member 115 rotatably supports an intermediate friction driving wheel 120 selectively engageable with driving roller 78 and with either driving wheel 90 or 100. Such selective engagement is provided by a combined rearward movement of bracket 115 and oscillation thereof from the position shown in Fig. 4, all in a manner to be described. A pair of arms 121 and 122 extend from either end of bracket 115 and support braking shoes 123, 124, which, in the inoperative position of the mechanism shown in Fig. 4, are engaged with driving wheels 90 and 100 respectively to maintain the same against rotation. For a purpose to be described, bracket 115 is further provided with a pair of depending abutments 126 and 127 extending obliquely on either side of the pivot support of intermediate driving wheel 120.

A pair of cooperating juxtaposed brackets 125 and 130 are commonly pivoted to the underside of base plate 66 by a stud 128. Adjacent its rearward end, bracket 125 is provided with depending ears 131 and 132 in which are adjustably mounted studs 133 and 134 provided with lock nuts 135. Upon swinging movement of bracket 125 in either direction, one of the studs 133 or 134 will engage one of the abutments 126 or 127 on bracket 115 to move the bracket rearwardly and oscillate it in one direction or the other. Adjacent its intermediate portion bracket 125 is provided with a pair of lugs 136 and 137 to which are secured leaf springs 138 and 140 respectively. Brake shoes 141 and 142 are secured on the outer end of leaf springs 138 and 140, and in the position shown in Fig. 4, are in engagement respectively with hub 88 associated with driving wheel 90 and with collar 104 on the hub of driving wheel 100. The purpose of this arrangement will be apparent as the description proceeds.

Near the forward end of bracket 125, a flange 143 depends therefrom through an arcuate slot 144 in bracket 130, and is connected by a coil spring 145 to the pivotal mounting 149 of intermediate driving wheel 120 to normally urge bracket 115 and its component elements to the forward position shown in Fig. 4. An upwardly extending flange 146 on the forward end of bracket 125 has secured thereto an upwardly and rearwardly bowed spring 147, on the inner end of which is a locking piece 148 having a depending detent 151 (Fig. 7) extending into a cam slot 152 in bracket 130. In the position shown in the drawings, detent 151 is engaged with the central notch of a latching member 153 secured to the forward wall 149 of base 66.

Bracket 130 is provided with a depending portion 154 to which control lever 27 is detachably secured for projection beyond front panel 16 of unit 15, and with depending lugs 154 and 155.

connected by springs 156 and 157 respectively to flange 143 of bracket 125.

The operation of the mechanism so far described is as follows. When control switch 23 is in the on position, motor 80 is continuously energized to rotate driving roller 78. With the control lever 27 in the intermediate position, intermediate driving wheel 120 is out of engagement with roller 78 and also out of engagement with driving wheels 90 and 100. The mechanism 85 then occupies the position shown in Fig. 4.

Brackets 125, 130 form a lost motion connection between selector lever 27 and mechanism 85. If lever 27 is moved to the "rewind" position, bracket 130 is oscillated clockwise as viewed in Fig. 4, and during the initial movement of bracket 130, no displacement of mechanism 85 occurs. However, as bracket 130 continues its clockwise movement, spring 156 is tensioned and cam slot 152, engaging detent 151, releases the detent from its engagement with the intermediate notch of member 153. When detent 151 is released from the intermediate slot, the tension of spring 156 snaps bracket 125 in the clockwise direction until detent 151 engages the right hand notch (Fig. 4) of member 153.

Such clockwise movement of bracket 125 decreases the pressure with which brake member 141 engages hub 88 and increases the pressure with which brake member 142 engages braking collar 104. Stud 134 thereupon engages ear 127 to move bracket 115 rearwardly and oscillate bracket 115 a slight amount in the clockwise direction. This releases shoes 123 and 124 from engagement with driving wheels 90 and 100 respectively. Intermediate driving wheel 120 is then engaged with driving roller 78 and with "rewind" driving roller 90. "Rewind" reel 40 is thus rotated in a direction to rewind wire 45 thereon, and at a relatively high rate of speed.

The unwinding of wire 45 from "storage" reel 41 effects rotation of this reel which, through coupling gears 48 and 51 rotates shaft 97. Through the reduction gearing previously described, gear 76 is thus rotated to operate the spooling mechanism and associated components in magazine 20, but at a reduced rate with respect to the rate of movement of wire 45. In a manner to be described, when substantially all of wire 45 has been rewound on wheel 40, motor 80 is automatically deenergized. In a similar manner, if control lever 27 were moved to the right as viewed in Figs. 1, 2 and 3, or to the left as viewed in Fig. 4, to the "recording and reproducing" position, intermediate driving wheel 120 would be engaged with driving roller 78 and with "storage" wheel 100 to wind wire 45 onto "storage" reel 41.

Normally motor 80 is energized for rotation in a direction to operate "storage" reel 41 to wind wire 45 thereon. Movement of bracket 125 into the "rewind" position operates switch mechanism to reverse the direction of rotation of motor 80 so that the motor will rotate "rewind" reel 40 in the correct direction to rewind wire 45 thereon. For this purpose, a switch unit 160 is mounted on base 66, and comprises a plurality of snap action switches indicated at 158 and 161. Referring more particularly to Figs. 5, 6 and 8, switches 158 and 161 are operable by a cam 162 pivoted on bracket 163 secured to wall 149 of base plate 66. A leaf spring 164 is secured to cam 162 for engaging the operating plungers of switches 158 and 161. Cam 162 is formed with a depending ear 165 extending into an aperture 166 in bracket 125 adjacent flange 143. Movement of

bracket 125 in response to movement of lever 27 to the "rewind" position operates cam 162 through ear 165 to in turn operate switches 158 and 161 from the position shown in Fig. 8 to the opposite position. This operation conditions motor 80 for operation in the reverse direction.

Means are provided for interrupting operation of the driving mechanism when wire 45 is completely rewound from one reel of the magazine onto the other. For this purpose, a bracket 170 is secured to the under surface of plate 22 near its rearward edge as viewed in Fig. 2. Referring more particularly to Figs. 5 and 9, bracket 170 supports a pair of snap action limit switches 171 and 172 controlling energization of motor 80 in either direction. A T-shaped operating member 74 is pivotally mounted at 173 on bracket 170 and has secured to each end leaf springs 174, 175 engaging the operating plungers of switches 171, 172. A pair of coil springs 176, 176 normally maintain the operating member 74 in the neutral position.

Operating member 74 projects above the surface of plate 22 and through a slot 177 in a laterally movable member 178 in magazine 20. Member 178 is movable along magazine 20 by means including gearing connected to the spooling mechanism driven by gear 76, all as described in my said copending application. Adjacent either limit of movement of wire 45, abutment means engage member 178 to move the same to the right or left, as viewed in Fig. 9, to correspondingly pivot member 74 and open one of the switches 171 or 172 to deenergize motor 80. Movement of laterally movable member 178 is effected by the mechanism shown in Figure 11. In this view laterally movable member 178 comprises the bent-up ears 185 and 186. Ear 185 is equipped with the adjustable abutment 187. Either ear 186 or adjustable abutment 187 is disposed to be engaged by nut 188 which is driven by threaded shaft 189. Nut 188 moves laterally along the shaft 189 and is locked against rotation by sliding engagement with a suitable surface. Shaft 189 is rotatably supported in pillow blocks 190 and 191 and is driven by bevelled gear 192. Bevelled gear 192 in turn receives its operating torque from mating bevelled gear 193. Bevelled gear 193 is driven by a gear 75a on the same shaft meshing with gear 76, the gear ratio therebetween being such that a predetermined speed ratio exists between the revolutions of the shaft 97 and of the gear 193.

Fig. 10 diagrammatically illustrates the operation of switches 158, 161, 171 and 172 in controlling the operation of motor 80. For purposes of illustration, motor 80 is shown as a shunt wound motor comprising an armature 180 and a shunt field winding 182 energized from a suitable source of electric current indicated by terminals 183, 184. The several switches are shown in the position they normally occupy when the selector 74 is in the neutral position. As explained, under such circumstances, motor 80 is energized for rotation in a direction to wind the recording wire on "storage" reel 41 for recording and reproducing. When selector 74 is thrown to the "rewind" position, flange 143 engages ear 165 to swing cam 162 counterclockwise reversing the position of switches 158 and 161. The motor is then energized for rotation in a direction to rewind recording wire 45 on "rewind" reel 40.

Limit switch 171 controls the limit of operation of motor 80 during the recording and reproducing operation. When substantially all of wire 45 has

been wound onto reel 41, member 178 engages selector 74 and swings it in a counterclockwise direction to open switch 171. This breaks the circuit of motor 80. However, when switches 158 and 161 are moved to the reverse position for rewinding wire 45, the energization of motor 80 is under the control of switch 172 which remains closed until such time as wire 45 has been substantially all rewound on reel 40. At such time, member 178 is moved to the right to swing selector 74 in a clockwise direction and open switch 172.

The described mechanism comprises an efficient, compact and easily serviceable sound recording or reproducing unit for use in a magazine type recording system. The unit includes a novel electromechanical control unit for conditioning the apparatus either for rewinding or for recording and reproducing. Furthermore, limit switch means are provided for automatically deenergizing the driving means when the magnetic recording wire has been substantially completely rewound from one reel to the other. Novel means are also provided for insuring that the wire is maintained in tension in either direction of movement.

While a specific embodiment of the invention has been shown and described in detail to illustrate the application of the principles thereof, it will be understood that the invention may be otherwise embodied without departing from such principles.

What is claimed is:

1. Magnetic sound translating apparatus comprising, in combination, a pair of rotatable reels for traversing a linear magnetic recording medium with respect to a magnetic translating head; a pair of driven members, each mechanically coupled to one of said reels, said driven members being spaced from each other; a driving member selectively movable into driving engagement with either of said driven members; and mechanism for selectively engaging said driving member with either of said driven members, said mechanism including a movable selector, a movable operator operative to selectively engage said driving member with either of said driven members, resilient means biasing said operator to follow the movements of said selector and means restraining movement of said operator in response to movement of said selector until said selector has approached its limit of movement in either direction, said last-named means thereupon releasing said operator to be biased in the same direction by said resilient means.

2. Magnetic sound translating apparatus comprising, in combination, a pair of rotatable reels for traversing a linear magnetic recording medium with respect to a magnetic translating head; a pair of driven members, each mechanically coupled to one of said reels, said driven members being spaced from each other; a driving member selectively movable into driving engagement with either of said driven members; driving means normally disengaged from said driving member; and mechanism for selectively engaging said driving member with either of said driven members and with said driving means, said mechanism including a movable selector, a movable operator operative to selectively engage said driving member with either of said driven members and with said driving means, resilient means biasing said operator to follow the movement of said selector and means restraining movement of said operator in response to move-

ment of said selector until said selector has approached its limit of movement in either direction, said last-named means thereupon releasing said operator to be biased in the same direction by said resilient means.

3. Magnetic sound translating apparatus comprising, in combination, a pair of rotatable reels for traversing a linear magnetic recording medium with respect to a magnetic translating head; a pair of driven members, each mechanically coupled to one of said reels, said driven members being spaced from each other; a driving member selectively movable into driving engagement with either of said driven members; normally ineffective brake means selectively operable on either of said driven members; and mechanism for selectively engaging said driving member with either of said driven members, said mechanism including a movable selector, a movable operator operative to selectively engage said driving member with either of said driven members and to render said brake means effective on the other driven member, resilient means biasing said operator to follow the movements of said selector and means restraining movement of said operator in response to movement of said selector until said selector has approached its limit of movement in either direction, said last-named means thereupon releasing said operator to be biased in the same direction by said resilient means.

4. Magnetic sound translating apparatus comprising, in combination, a pair of rotatable reels for traversing a linear magnetic recording medium with respect to a magnetic translating head; a pair of driven members, each mechanically coupled to one of said reels, said driven members being spaced from each other; a driving member selectively movable into driving engagement with either of said driven members; a pair of brakes each normally engaged with one of said driven members; and mechanism for selectively engaging said driving member with either of said driven members, said mechanism including a movable selector, a movable operator operative to selectively engage said driving member with either of said driven members and to disengage both of said brakes, resilient means biasing said operator to follow the movements of said selector and means restraining movement of said operator in response to movement of said selector until said selector has approached its limit of movement in either direction, said last-named means thereupon releasing said operator to be biased in the same direction by said resilient means.

5. Magnetic translating apparatus comprising, in combination, a pair of rotatable reels for traversing a linear magnetic recording medium with respect to a magnetic translating head; a pair of driven members, each mechanically coupled to one of said reels, said driven members being spaced from each other; a driving member selectively movable into driving engagement with either of said driven members; a pair of brakes each normally engaged with one of said driven members; normally ineffective brake means selectively operable on either of said driven members; and mechanism for selectively engaging said driving member with either of said driven members, said mechanism including a movable selector, a movable operator operative to selectively engage said driving member with either of said driven members, to disengage both of said brakes and to render said brake means effective

on the other driven member, resilient means biasing said operator to follow the movements of said selector and means restraining movement of said operator in response to movement of said selector until said selector has approached its limit of movement in either direction, said last-named means thereupon releasing said operator to be biased in the same direction by said resilient means.

6. Magnetic sound translating apparatus comprising, in combination, a pair of rotatable reels for traversing a linear magnetic recording medium with respect to a magnetic translating head; a pair of driven members, each mechanically coupled to one of said reels, said driven members being spaced from each other; a driving member selectively movable into driving engagement with either of said driven members; driving means normally disengaged from said driving member; a pair of brakes each normally engaged with one of said driven members; normally ineffective brake means selectively operable on either of said driven members; and mechanism for selectively engaging said driving member with either of said driven members, said mechanism including a movable selector, a movable operator operative to selectively engage said driving member with either of said driven members and with said driving means, to disengage both of said brakes and to render said brake means effective on the other driven member; resilient means biasing said operator to follow the movements of said selector and means restraining movement of said operator in response to movement of said selector until said selector has approached its limit of movement in either direction, said last-named means thereupon releasing said operator to be biased in the same direction by said resilient means.

7. Magnetic sound translating apparatus comprising, in combination, a pair of spaced rotatable reels for traversing a linear magnetic recording medium with respect to a magnetic translating head; a pair of rotatable driven members, each mechanically coupled to one of said reels, said rotatable driven members being spaced from each other; a rotatable idler selectively movable into driving engagement with either of said driven members; a rotatable driving member normally disengaged from said idler; an electric motor coupled to said driving member; a movable selector; a movable operator operative to selectively engage said idler with either of said rotatable driven members; resilient means biasing said operator to follow the movements of said selector; means restraining movement of said operator in response to movement of said selector until said selector has approached its limit of movement in either direction, said last-named means thereupon releasing said operator to be biased in the same direction by said resilient means; and mechanism coupled to one of said driven members and operable automatically in response to a predetermined number of revolutions of one of said reels to effect deenergization of said motor.

8. Magnetic sound translating apparatus comprising, in combination, a pair of spaced rotatable reels for traversing a linear magnetic recording medium with respect to a magnetic translating head; a pair of rotatable driven members, each mechanically coupled to one of said reels, said rotatable driven members being spaced from each other; a rotatable idler selectively movable into driving engagement with either of said driven

members; a rotatable driving member normally disengaged from said idler; an electric motor coupled to said driving member; a movable selector; a movable operator operative to selectively engage said idler with either of said rotatable driven members; brake means movable by said operator into effective engagement with the other driven member; resilient means biasing said operator to follow the movements of said selector; means restraining movement of said operator in response to movement of said selector until said selector has approached its limit of movement in either direction, said last-named means thereupon releasing said operator to be biased in the same direction by said resilient means; and mechanism coupled to one of said driven members and operable automatically in response to a predetermined number of revolutions of one of said reels to effect deenergization of said motor.

9. Magnetic sound translating apparatus comprising, in combination, a pair of spaced rotatable reels for traversing a linear magnetic recording medium with respect to a magnetic translating head; a pair of rotatable driven members, each mechanically coupled to one of said reels, said rotatable driven members being spaced from each other; a pair of brakes each normally engaged with one of said driven members; a rotatable idler selectively movable into driving engagement with either of said driven members; a rotatable driving member normally disengaged from said idler; an electric motor coupled to said driving member; a movable selector; a movable operator operative to selectively engage said idler with either of said rotatable driven members and to disengage both of said brakes; resilient means biasing said operator to follow the movements of said selector; means restraining movement of said operator in response to movement of said selector until said selector has approached its limit of movement in either direction, said last-named means thereupon releasing said operator to be biased in the same direction by said resilient means; and mechanism coupled to one of said driven members and operable automatically in response to a predetermined number of revolutions of one of said reels to effect deenergization of said motor.

10. Magnetic sound translating apparatus comprising, in combination, a pair of spaced rotatable reels for traversing a linear magnetic recording medium with respect to a magnetic translating head; a pair of rotatable driven members, each mechanically coupled to one of said reels, said rotatable driven members being spaced from each other; a pair of brakes each normally engaged with one of said driven members; a rotatable idler selectively movable into driving engagement with either of said driven members; a rotatable driving member normally disengaged from said idler; an electric motor coupled to said driving member; a movable selector; a movable operator operative to selectively engage said idler with either of said rotatable driven members and to disengage both of said brakes; brake means movable by said operator into effective engagement with the other driven member; resilient means biasing said operator to follow the movements of said selector; means restraining movement of said operator in response to movement of said selector until said selector has approached its limit of movement in either direction, said last-named means thereupon releasing said operator to be biased in the same direction by said resilient means; and mechanism coupled to one of said driven members and operable automatically in response to a predetermined number of revolutions of one of said reels to effect deenergization of said motor.

12. mined number of revolutions of one of said reels to effect deenergization of said motor.

11. Magnetic sound translating apparatus comprising, in combination, a storage reel and a rewind reel for traversing a linear magnetic recording medium with respect to a magnetic translating head; a pair of rotatable driven members, each mechanically coupled to one of said reels, said rotatable driven members being spaced from each other; a rotatable idler selectively movable into driving engagement with either of said driven members; a rotatable driving member normally disengaged from said idler; an electric motor coupled to said driving member; a selector movable from a neutral position to a first "recording and reproducing" position or to a second "rewind" position; a movable operator operative to selectively engage said idler with said driving member and with either the driven member coupled to the storage reel or the driven member coupled to the rewinding reel dependent upon movement of said selector to either said first position or said second position; means biasing said operator to follow the movements of said selector; a switch operable to reverse the direction of rotation of said motor; and an element coupled to said operator and effective to operate said switch to reverse said motor when said selector is moved to said second position.

12. Magnetic sound translating apparatus comprising, in combination, a storage reel and a rewind reel for traversing a linear magnetic recording medium with respect to a magnetic translating head; a pair of rotatable driven members, each mechanically coupled to one of said reels, said rotatable driven members being spaced from each other; a rotatable idler selectively movable into driving engagement with either of said driven members; a rotatable driving member normally disengaged from said idler; an electric motor coupled to said driving member; a selector movable from a neutral position to a first "recording and reproducing" position or to a second "rewind" position; a movable operator operative to selectively engage said idler with said driving member and with either the driven member coupled to the storage reel or the driven member coupled to the rewinding reel dependent upon movement of said selector to either said first position or said second position; resilient means biasing said operator to follow the movements of said selector; means restraining movement of said operator in response to movement of said selector until said selector has approached its limit of movement in either direction, said last-named means thereupon releasing said operator to be biased in the same direction by said resilient means; an element coupled to said operator and effective to operate said switch to reverse said motor when said selector is moved to said second position; and mechanism coupled to one of said driven members and operable in response to a predetermined number of revolutions of one of said reels to effect deenergization of said motor.

13. Magnetic sound translating apparatus comprising, in combination, a pair of spaced rotatable reels for traversing a linear magnetic recording medium with respect to a magnetic translating head; a supporting plate; a pair of friction driven wheels rotatably mounted on said plate and each operatively coupled to one of said reels; a manually operable selector pivotally secured to said plate intermediate said reels; a bracket pivotally mounted on said plate, said selector and said bracket having a common pivot center; resilient

means biasing said bracket to follow the movements of said selector; a latch fixed to said plate; a latching bar on said bracket releasably engaging said latch, said latch and bar preventing movement of said bracket in response to movement of said selector; a cam on said selector engaging said latching bar, said cam releasing said bar from said latch when said selector approaches its limit of movement in either direction, whereupon said resilient means bias said bracket into substantial coincidence with said selector; a driving roller rotatably mounted on said plate; an electric motor coupled to said driving roller; an idler wheel movably mounted on said plate intermediate and normally out of engagement with said driven wheels; means normally maintaining said idler wheel out of engagement with said driving roller; and mechanism operable by movement of said bracket under the influence of said resilient means to engage said idler wheel with said driving roller and selectively with one of said driven wheels.

14. Magnetic sound translating apparatus comprising, in combination, a pair of spaced rotatable reels for traversing a linear magnetic recording medium with respect to a magnetic translating head; a supporting plate; a pair of friction driven wheels rotatably mounted on said plate and each operatively coupled to one of said reels; a manually operable selector pivotally secured to said plate intermediate said reels; a bracket pivotally mounted on said plate, said selector and said bracket having a common pivot center; a pair of brake means mounted on said bracket and each cooperable with a driven wheel; resilient means biasing said bracket to follow the movements of said selector; a latch fixed to said plate; a latching bar on said bracket releasably engaging said latch, said latch and bar preventing movement of said bracket in response to movement of said selector; a cam on said selector engaging said latching bar, said cam releasing said bar from said latch when said selector approaches its limit of movement in either direction, whereupon said resilient means bias said bracket into substantial coincidence with said selector; a driving roller rotatably mounted on said plate; an electric motor coupled to said driving roller; an idler wheel movably mounted on said plate intermediate and normally out of engagement with said driven wheels; means normally maintaining said idler wheel out of engagement with said driving roller; and mechanism operable by movement of said bracket under the influence of said resilient means to engage said idler wheel with said driving roller and selectively with one of said driven wheels, such movement of said bracket effectively engaging one of said brake means with the other driven wheel.

15. Magnetic sound translating apparatus comprising, in combination, a pair of spaced rotatable reels for traversing a linear magnetic recording medium with respect to a magnetic translating head; a supporting plate; a pair of friction driven wheels rotatably mounted on said plate and each operatively coupled to one of said reels; a manually operable selector pivotally secured to said plate intermediate said reels; a bracket pivotally mounted on said plate, said selector and said bracket having a common pivot center; resilient means biasing said bracket to follow the movements of said selector; a latch fixed to said plate; a latching bar on said bracket releasably engaging said latch, said latch and bar preventing movement of said bracket in response to movement of said selector; a cam on

said selector engaging said latching bar, said cam releasing said bar from said latch when said selector approaches its limit of movement in either direction, whereupon said resilient means bias said bracket into substantial coincidence with said selector; a driving roller rotatably mounted on said plate; an electric motor coupled to said driving roller; an idler wheel movably mounted on said plate intermediate and normally out of engagement with said driven wheels; means normally maintaining said idler wheel out of engagement with said driving roller; mechanism operable by movement of said bracket under the influence of said resilient means to engage said idler wheel with said driving roller and selectively with one of said driven wheels; and a pair of brakes each normally engaged with one of said driven wheels; such movement of said bracket disengaging said brakes from said driven wheels.

16. Magnetic sound translating apparatus comprising, in combination, a pair of spaced rotatable reels for traversing a linear magnetic recording medium with respect to a magnetic translating head; a supporting plate; a pair of friction driven wheels rotatably mounted on said plate and each operatively coupled to one of said reels; a manually operable selector pivotally secured to said plate intermediate said reels; a bracket pivotally mounted on said plate, said selector and said bracket having a common pivot center; a pair of brake means mounted on said bracket and each cooperable with a driven wheel; resilient means biasing said bracket to follow the movements of said selector; a latch fixed to said plate; a latching bar on said bracket releasably engaging said latch, said latch and bar preventing movement of said bracket in response to movement of said selector; a cam on said selector engaging said latching bar, said cam releasing said bar from said latch when said selector approaches its limit of movement in either direction, whereupon said resilient means bias said bracket into substantial coincidence with said selector; a driving roller rotatably mounted on said plate; an electric motor coupled to said driving roller; an idler wheel movably mounted on said plate intermediate and normally out of engagement with said driven wheels; means normally maintaining said idler wheel out of engagement with said driving roller; mechanism operable by movement of said bracket under the influence of said resilient means to engage said idler wheel with said driving roller and selectively with one of said driven wheels; and a pair of brakes each normally engaged with one of said driven wheels; such movement of said bracket effectively engaging one of said brake means with the other driven wheel and disengaging said brakes from said driven wheels.

17. In a magazine type magnetic sound translating apparatus including a magazine containing a pair of reels for traversing a linear magnetic recording medium with respect to a magnetic translating head, spooling mechanism for layer winding the medium onto and off of the reels and mechanical coupling means for each of the reels and for the spooling mechanism, a sound translating unit interchangeably cooperative with the magazine comprising a casing; a mounting plate mounted in said casing; a magazine supporting plate; a pair of shaft housings interconnecting said plates in vertically disposed relation; a pair of shafts each rotatably mounted in one of said housings; a coupling element on the upper end of each shaft projecting through said sup-

porting plate for detachable cooperation with the reel coupling means of the magazine; a coupling gear projecting through said supporting plate for cooperation with the spooling mechanism coupling means; reduction gearing connecting said coupling gear to one of said shafts; a pair of friction driven wheels each secured to the lower end of one of said shafts; a driving roller rotatably mounted on said mounting plate; an electric motor coupled to said driving roller; an idler wheel normally mounted on said mounting plate intermediate and normally out of engagement with said driven wheels; a manually operable selector pivotally secured to said plate intermediate said wheels; a movable operator operative to selectively engage said idler wheel with either of said driven wheels and with said driving roller; resilient means biasing said operator to follow the movements of said selector; and means restraining movement of said operator in response to movement of said selector until said selector has approached its limit of movement in either direction, said last-named means thereupon releasing said operator to be biased in the same direction by said resilient means.

18. In a magazine type magnetic sound translating apparatus including a magazine containing a pair of reels for traversing a linear magnetic recording medium with respect to a magnetic translating head, spooling mechanism for layer winding the medium onto and off of the reels and mechanical coupling means for each of the reels and for the spooling mechanism, a sound translating unit interchangeably cooperative with the magazine comprising a casing; a mounting plate mounted in said casing; a magazine supporting plate; a pair of shaft housings interconnecting said plates in vertically disposed relation; a pair of shafts each rotatably mounted in one of said housings; a coupling element on the upper end of each shaft projecting through said supporting plate for detachable cooperation with the reel coupling means of the magazine; a coupling gear projecting through said supporting plate for cooperation with the spooling mechanism coupling means; reduction gearing connecting said coupling gear to one of said shafts; a pair of friction driven wheels each secured to the lower end of one of said shafts; a driving roller rotatably mounted on said mounting plate; an electric motor coupled to said driving roller; an idler wheel normally mounted on said mounting plate intermediate and normally out of engagement with said driven wheels; a manually operable selector pivotally secured to said plate intermediate said wheels; a movable operator operative to selectively engage said idler wheel with either of said driven wheels and with said driving roller; resilient means biasing said operator to follow the movements of said selector; and means restraining movement of said operator in response to movement of said selector until said selector has approached its limit of movement in either direction, said last-named means thereupon releasing said operator to be biased in the same direction by said resilient means; a switch secured to said supporting plate and controlling the energization of said motor; and an operator for said switch projecting above said supporting plate for cooperation with an element of the magazine operable by said reduction gearing and coupling gear, in response to transfer of substantially all of the medium from one reel to the other, to move said operator to condition said switch to deenergize said motor.

19. In a magazine type magnetic sound translating apparatus including a magazine containing a pair of reels for traversing a linear magnetic recording medium with respect to a magnetic translating head, spooling mechanism for layer winding the medium onto and off of the reels and mechanical coupling means for each of the reels and for the spooling mechanism, a sound translating unit interchangeably cooperative with the magazine comprising a casing; a mounting plate mounted in said casing; a magazine supporting plate; a pair of shaft housings interconnecting said plates in vertically disposed relation; a pair of shafts each rotatably mounted in one of said housings; a coupling element on the upper end of each shaft projecting through said supporting plate for detachable cooperation with the reel coupling means of the magazine; a coupling gear projecting through said supporting plate for cooperation with the spooling mechanism coupling means; reduction gearing connecting said coupling gear to one of said shafts; a pair of friction driven wheels each secured to the lower end of one of said shafts; a driving roller rotatably mounted on said mounting plate; an electric motor coupled to said driving roller; an idler wheel normally mounted on said mounting plate intermediate and normally out of engagement with said driven wheels; a manually operable selector pivotally secured to said plate intermediate said wheels; a movable operator operative to selectively engage said idler wheel with either of said driven wheels and with said driving roller; resilient means biasing said operator to follow the movements of said selector; and means restraining movement of said operator in response to movement of said selector until said selector has approached its limit of movement in either direction, said last-named means thereupon releasing said operator to be biased in the same direction by said resilient means; spaced latches pivotally mounted on said supporting plate and automatically engageable with latching means on the magazine when the latter is placed on said supporting plate; and manually operable releasing means for said latches.

20. Magnetic sound translating apparatus comprising, in combination, a pair of spaced rotatable reels for traversing a linear magnetic recording medium with respect to a magnetic translating head; a supporting plate; a pair of friction driven wheels rotatably mounted on said plate and each operatively coupled to one of said reels; a manually operable selector pivotally secured to said plate intermediate said reels; a bracket pivotally mounted on said plate, said selector and said bracket having a common pivot center; resilient means biasing said bracket to follow the movements of said selector; a latch fixed to said plate; a latching bar on said bracket releasably engaging said latch, said latch and bar preventing movement of said bracket in response to movement of said selector; a cam on said selector engaging said latching bar, said cam releasing said bar from said latch when said selector approaches its limit of movement in either direction, whereupon said resilient means bias said bracket into substantial coincidence with said selector; a driving roller rotatably mounted on said plate in alignment with such common pivot point; an electric motor coupled to said driving roller; a second bracket mounted on said plate intermediate such common pivot point and said driving roller for movement either longitudinally or laterally thereof; an idler wheel movably mounted

17

on said second bracket intermediate and normally out of engagement with said driven wheels; resilient means biasing said second bracket forwardly of said plate to maintain said driving roller and said idler wheel disengaged; a pair of tappets mounted on the first-named bracket; and a pair of abutments on said second bracket respectively cooperative with said tappets; movement of said bracket in response to movement of said selector selectively striking one of said tappets against its associated abutment to drive said second bracket rearwardly of said plate to engage

10

18

said idler wheel with said roller and laterally of said plate to engage said idler wheel selectively with one of said driven wheels.
